UNITED STATES PATENT OFFICE.

ERNST NÄGELIN, OF BASEL, SWITZERLAND.

APPARATUS FOR THE TREATMENT OF TEXTILE GOODS IN HANK FORM BY MEANS OF CIRCULATING LIQUIDS.

1,367,494.

Specification of Letters Patent. Patented Feb. 1, 1921.

Application filed April 26, 1920. Serial No. 376,786.

To all whom it may concern:

Be it known that I, ERNST NÄGELIN, a citizen of the Swiss Republic, and resident of Basel, Switzerland, have invented a new and useful Apparatus for the Treatment of Textile Goods in Hank Form by Means of Circulating Liquids.

This invention relates to an apparatus for the treatment of textile goods in hank or skein form by means of circulating liquid.

According to the invention the hanks or skeins are suspended upon perforated tubes which are horizontally mounted in bearings at one end and are supplied with liquid under slight pressure, which liquid flows through the perforations in the tubes and runs downward along the skeins or hanks. The treatment of the textile goods by the liquid can be evenly distributed by causing the tubes to be periodically turned in order to change the point of suspension of the hanks on the tubes.

The accompanying drawing illustrates one form of apparatus for carrying out the invention.

In the said drawing:

Figure 1 is a sectional elevation of the apparatus and

Fig. 2 is a part plan view thereof.

The centrifugal pump A draws liquid, for example, washing water, from the container B and forces it under slight pressure through a common horizontal tube *a* into the tubes C which are arranged at right angles to the latter and the upper part of each of which is furnished with fine perforations. The liquid escapes through the perforations in the said tubes C into the textile goods at the points of suspension of the latter on the tubes C and flows down the hanks in evenly divided streams back into the container B.

To enable the textile goods to be evenly treated throughout with the liquid the tubes C have keyed upon them toothed wheels *b* of the same diameter and which mesh with one another, one of the said toothed wheels engaging with a toothed pinion *c* which is so connected with a driving device that it can be periodically rotated so as thereby to impart periodically to the tubes C one or more complete rotations and thereby to change the points of suspension of the hanks or skeins on the tubes.

In the form of apparatus illustrated the tubes C are rotatably mounted in branches *d* of the horizontal tube *a*; they may however

be supported at their supporting end in any other suitable bearings.

Applicant is aware of the fact that apparatuses are known for the treatment with circulating liquids of hanks or skeins suspended on horizontal hank carriers, rotatably mounted at one end and provided with perforations. But in the previously known apparatuses of this kind, each hank carrier especially shaped as reel, hollow roller, ribbed tubes or the like was, when rotatable, always combined with a further horizontal tube for the supply of the liquid to the hank carrier, while according to the present invention a single perforated horizontal tube serves simultaneously as hank carrier and as tube for the supply of the liquid.

What I claim is:

1. In an apparatus for the treatment of textile goods in hank or skein form by means of circulating liquid, comprising horizontal hank carriers, on which the hanks are to be suspended and which are rotatably mounted at one end and furnished with perforations, each hank carrier formed singly by a rotatable tube only perforated at its upper part, connected to a device for supplying liquid under slight pressure and serving simultaneously as hank carrier and for the supply of liquid, so that the liquid which escapes at the points of suspension of the hanks on the tube flows down along the hanks or skeins.

2. In an apparatus for the treatment of textile goods in hank or skein form by means of circulating liquid, comprising horizontal hank carriers, on which the hanks are to be suspended and which are rotatably mounted at one end and furnished with perforations, each hank carrier formed singly by a rotatable tube only perforated at its upper part, connected to a device for supplying liquid under a slight pressure and serving simultaneously as hank carrier and for the supply of liquid, the said tube being combined with means to impart periodically to it at least one complete rotation and thereby to change the points of suspension of the hanks or skeins.

In witness whereof I have hereunto signed my name this 9th day of April, 1920, in the presence of two subscribing witnesses.

ERNST NÄGELIN.

Witnesses:

WILLIAM E. HOLLAND,
AMAND RITTER.
